DELIVERY CONTROL APPARATUS
Jack Dreeben, Wyndmoor, Pa.
(2601 N. Howard St., Philadelphia, Pa.)
Filed Oct. 9, 1963, Ser. No. 315,068
15 Claims. (Cl. 53—78)

This invention relates to article delivery control apparatus and more particularly to apparatus for delivering predetermined quantities of articles, measured as to number for packaging.

In the delivery of articles for packaging in quantities measured as to number or weight difficulties arise, particularly at the package machinery because of jamming of the articles together at some critical location such as at the funnel entrance to the packaging machine feed tube. Numerous devices have heretofore been proposed for interrupting the continuous flow or holding back some of the articles to permit sealing a measured quantity in a package. The time required for operation or the inertia of the moving parts of the devices heretofore proposed prevented utilization of such devices.

It is the principal object of the present invention to provide article delivery control apparatus for measured quantities of articles from a continuously operating source which provides a timed interruption in the flow and accommodation of the interruption to the operation of a packaging machine.

It is a further object of the present invention to provide article delivery control apparatus for measured quantities of articles having a movable receiver for articles to be retained during interruption of the delivery for package sealing or the like.

It is a further object of the present invention to provide article delivery control apparatus which is simple in construction, free from likelihood of operating difficulties and easy to keep clean.

It is a further object of the present invention to provide article delivery control apparatus which includes a rotating platform or table which serves as a temporary storage location to accommodate interruptions in continuous flow of articles to be packaged.

It is a further object of the present invention to provide article feed control apparatus which permits of measured delivery of articles to be packaged at speeds many times greater than heretofore.

Other objects and advantageous features of the invention will be apparent from the description and claims.

The nature and characteristic features of the invention will be more readily understood from the following description taken in connection with the accompanying drawings forming part thereof, in which:

FIGURE 1 is a diagrammatic view of article feed control apparatus in accordance with the invention applied to a packaging machine;

FIG. 2 is a side elevational view, enlarged, of the feed control apparatus shown in FIG. 1;

FIG. 3 is a top plan view of the apparatus shown in FIG. 2;

FIG. 4 is a vertical sectional view, enlarged, taken approximately on the line 4—4 of FIG. 3; and

FIG. 5 is a horizontal sectional view taken approximately on the line 5—5 of FIG. 4.

It should, of course, be understood that the description and drawings herein are illustrative merely, and that various modifications and changes can be made in the structure disclosed without departing from the spirit of the invention.

Like numerals refer to like parts throughout the several views.

Referring first to FIG. 1 of the drawings, for purposes of explanation it may be noted that it has heretofore been

2

proposed to provide package making machines which include a web roll having thereon a supply of sheet material to be made into a succession of longitudinally sealed tubular packages with transverse seals at each end.

5 The prior package making machines also included a funnel 10 having therebelow a forming shoe 11 to which the sheet material was advanced from the supply on the web roll, the advancing being effected by a pair of horizontally separable gripping jaws 12 in engagement with the tubular web. The gripping jaws 12, customarily provided with heat sealing portions 13 were reciprocated in a vertical path by their supports 14, the length of the stroke determining the length of the package. The supports 14 were separated at the bottom of the stroke and moved upwardly in open position, then closed at the top of their stroke to bring the heat sealing portions 13 of the jaws 12 into gripping relation to the tubular conformation of the sheet material provided by the forming shoe 11.

Either during a period of rest or during the downward movement of the web of sheet material a longitudinal seal was provided by a longitudinal heat sealer 15 and the articles were delivered into the tubular formed web through a filling tube 17 formed as a continuation of the funnel 10 and interiorly disposed in spaced relation to the forming shoe 11.

During the downward movement of the jaws 12, also, a transverse seal was applied to the tubular sheet material which was severed intermediate the top and bottom margins of the transversely sealed area so that the transverse seal provided a sealed transverse top margin of the filled package and a sealed transverse bottom margin of the package to be filled. Repetition of the operations just referred to provided a succession of filled, sealed and separated packages.

35 Control apparatus in accordance with the invention is shown generally at 16.

The continuous feeding of articles to be packaged, where an exact count is desired, has resulted in difficulties in relation to the timed operation of the packaging machine and particularly with some articles jamming together at the entrance to the funnel 10.

Referring now more particularly to FIGS. 2 to 5 of the drawings a preferred embodiment of delivery control apparatus 16 in accordance with the invention is there illustrated.

45 A main article delivery conveyor 20 is provided by which the articles are delivered for packaging. Aligned with the conveyor 20 for receiving the articles therefrom a horizontal conveyor 21 is provided, which includes an endless belt 22 mounted on supporting rollers 23 and 24. The rollers 23 and 24 are shown as carried by shafts 25 and 26, respectively, journaled in a frame 27. A belt tightening roller 28 can be provided, mounted on the frame 27 and engaging the belt 22.

50 The belt 22 can be driven in any desired manner such as by a driving belt 29 engaging a pulley 30 secured to the shaft 26 and in turn driven by a motor 31.

The frame 27 has a control gate 35 mounted thereon on a horizontal pivot pin 36, the gate 35 preferably having a concavely curved face 37 to facilitate the movement of the articles advanced by the belt 22.

65 The gate 35 can be controlled as to its position with respect to the discharge end of the conveyor belt 22 in any desired manner. A suitable mechanism for this purpose includes a solenoid 38 pivotally mounted on the frame 27 and having an armature 39 with a pivotal connection 40 to the gate 35. The solenoid 38 has energizing leads 41.

The solenoid 38 can be controlled as desired but as shown a light sensitive cell 42 is provided for sensing articles as they pass.

The light cell 42 can have a light source 43 oppositely

disposed so that the cell 42 can furnish current pulses corresponding to the articles to a counter 45, adjustable as to the number of pulses required to provide an output pulse to the leads 41.

The counter 45 can have a gate reset pulse applied thereto in any desired manner, such as by the movement of the jaws 12 or support 14.

The gate 35 in open position does not obstruct the flow of articles which can move freely off the end of the belt 22 and into the funnel 10.

The gate 35 in lowered position diverts the articles and a rotary table 50 is provided for receiving the same. The table 50 is mounted on a vertical stub shaft 51 journaled in a horizontal bracket plate 52 which is carried by the frame 27. The table 50 can be actuated in any desired manner but preferably has a vertical endless band 53 in engagement with the major portion of its periphery.

The band 53 is supported and positioned by rollers 54 and 55 journaled in the plate 52 which hold the band 53 in peripheral engagement and is supported by spaced rollers 56, 57 and 58, also journaled in the plate 52, which guide the portions of the band which are remote from the periphery of the table 50. The open space along the periphery of the table 50 between the rollers 54 and 55 is of the order of one sixteenth of the periphery and is located with respect to the funnel 10 (see FIG. 3) so as to discharge an article which has been moved around on the table 50 by centrifugal action into the space above the funnel 10.

The band 53 can be driven in any desired manner to rotate the rotary table 50, one suitable drive comprising a pulley 59 on one of the rollers such as the roller 55, connected by a belt 60 to a pulley 61 carried on the shaft 26.

The mode of operation will now be pointed out.

The conveyor 20 in its normal movement delivers, preferably in a single line, the articles to be packaged, onto the conveyor belt 22. The conveyor belt 22 advances carrying the articles thereon to the funnel 10 for discharge thereinto. When the gate 35 is in its elevated or open position (see FIG. 2) the free discharge of articles into the funnel 10 is effected.

In the normal operation of a packaging machine of the type illustrated diagrammatically in FIG. 1, the jaws 12 draw the packaging material from the source over the shoe 11 and downwardly around the forming tube 17. During the downward movement of the jaws 12 a longitudinal seal can be provided by the sealer 15, and transverse sealing of the packaging material is effected. The transverse sealing provides a bottom boundary of the package, a top boundary of a previously filled package, and severing between the boundaries can be effected to separate the previously formed package. During the downward movement of the packaging material by the jaws 12, the articles to be packaged are delivered to and through the funnel 10 and forming tube 17.

At the bottom of their downward path the jaws 12 separate, move upwardly to the upper end of their stroke and come together into gripping engagement with the packaging material, and move downwardly repeating their cycle.

As the jaws 12 are coming together at the upper part of their stroke any articles present at that location would be gripped and the transverse seal could not be effected.

The gate 35, controlled as hereinafter explained with the table 50, obviates the difficulty just referred to as to jaw operation.

The counter 45 is adjusted so as to perform its operation in proper relation to the jaw cycle so that as the jaws 12 close feed of articles into the funnel 10 is temporarily discontinued.

This is effected by a count of articles passing the photo-sensitive cell 42, of predetermined number, causing the solenoid 38 to be energized to move the armature 39 to

lower the gate 35. The gate 35, in lowered condition (see FIG. 4), causes articles to be diverted by the face 37 of the gate 35 downwardly onto the table 50 which, for discharge thereon at one side of the funnel is rotating clockwise. The articles deposited onto the table 50 move around in a generally circular path and are discharged centrifugally from the table 50 at the open location between the belt 22 and the roller 55.

The band 53 not only rotates the rotary table 50 but by its movement with the table 50 facilitates the movement of the articles. The time elapsed between the delivery of one of several articles onto the table 50 and the discharge of that article into the funnel 10 provides the necessary time interval to permit closing of the jaw 12 for their downward movement without an article being caught therebetween.

The solenoid 38 can be reset in any desired manner, by a built in adjustable timing device in the counter 45, by the attainment of a predetermined count at the counter 45, or by a contact carried by one of the jaws 12.

The cycle of retention of articles can be repeated continuously as the package formation is continuously carried out.

I claim:

- 25 1. Apparatus for controlling the delivery of articles to a packaging machine having reciprocable jaws for advancing packaging material to form a package comprising a linearly advancing article carrying means having a discharge end, a movable gate at said discharge end and having a plurality of positions for article delivery control, a member for receiving articles for delivery to the packaging machine, and a member for temporary reception of articles, said gate positions determining the selective delivery of articles to said members.
- 30 2. Apparatus as defined in claim 1 in which said last member is a movable table.
- 35 3. Apparatus as defined in claim 1 in which said last member is a rotary table.
- 40 4. Apparatus as defined in claim 1 in which said last member is a rotary table and a peripheral portion of said table is in article delivery relation to said first member.
- 45 5. Apparatus as defined in claim 1 in which said last member is a rotary table and has a band around a portion of the periphery thereof.
- 50 6. Apparatus as defined in claim 5 in which said band is movable with said table.
- 55 7. Apparatus as defined in claim 5 in which said band is movable and is in driving engagement with said table.
- 60 8. Apparatus as defined in claim 1 having a light sensitive member for controlling the positioning of said gate.
- 65 9. Apparatus as defined in claim 1 having a counter for controlling said gate and a light sensitive member for controlling said counter in scanning relation to said carrying means.
- 70 10. In combination with an article packaging machine having an article delivery tube, a conveyor for delivering articles to said tube, and means for diverting articles interposed between conveyor and said tube comprising a movable article storage member, a gate for diverting articles onto said storage member, and article controlled control means for said gate.
- 75 11. The combination defined in claim 10 in which said article storage member is a rotary table having a discharge portion communicating with said delivery tube.
- 80 12. The combination defined in claim 10 in which said article storage member is a rotary table, and said table has a movable band extending around a portion of the periphery of said table, said band having spaced portions along said periphery for discharge of articles to said delivery tube.
- 85 13. The combination as defined in claim 12 in which said article storage member is a rotary table, said conveyor extends across and is terminated inwardly from the pe-

riphery of said table, said table has a movable band extending around a portion of the periphery thereof and said table has an open peripheral portion communicating with said delivery tube.

14. The combination as defined in claim 12 in which said article storage member is a rotary table, said table has a movable band around a portion of the periphery

thereof, and common driving means is provided for said conveyor and said band.

15. The combination as defined in claim 14 in which said band is in driving engagement with said rotary table.
